UNITED STATES PATENT OFFICE.

CHARLES M. HEUBLEIN, OF CHICAGO, ILLINOIS.

WINDOW ATTACHMENT.

Application filed November 26, 1926. Serial No. 150,685.

My invention relates to certain novel improvements in window attachments and has for one object the provision of a window attachment adapted to lift a window curtain when the window sash is lifted. Another object is the provision of means for permitting the lifting of the curtain from the attachment in order to permit access to the sash, for example, for window washing. Other objects will appear from time to time in the course of the specifications and claims.

I illustrate my invention more or less diagrammatically in the accompanying drawings, wherein—

15 Figure 1 is an elevational view of a window showing the invention associated therewith;

Figure 2 is a section on the line 2—2 of Figure 1;

20 Figure 3 is a front elevation of the attachment shown in Figure 1;

Figure 4 is an elevational view showing the curtain withdrawn from the attachment; and

25 Figure 5 is a detail.

Like parts are indicated by like symbols throughout the specifications and drawings.

Referring to the drawings, C indicates any suitable window frame having the lower and 30 vertically removable sash C¹. C² is any suitable supporting means for the upper end of the curtain C³.

Mounted upon the sash C¹ at each side thereof, are the bracket members D to which 35 are pivoted the levers D¹ with the long arms D² and the short arms D³. Removably secured to the outer ends of the arms D² is any suitable curtain engaging and raising member, herein shown as a rod D⁴ seated in notches D⁵ and secured in position for example by the hooks D⁶. Mounted on the window frame, above the normal position of the sash C¹, are the vertical tracks E which terminate at their lower ends in inclined or 40 curved cam or stop portions E¹, so formed as to engage the lever arms D³ to cause rotation of the lever, in response to the initial lifting of the sash, from the position in which it is shown in full line to the position 45 in which it is shown in dotted line in Figure 2.

The rods D⁴ may engage or be secured to a curtain in any suitable manner. Preferably it is in some way secured to the curtain 50 so that lifting of the rod necessarily lifts the

curtain. I illustrate it herein as threaded through the double portion C⁵ of the curtain.

Whenever it is necessary to withdraw the curtain from the window, for example when a window-washer wishes access to it the curtain may be lifted from a raising mechanism. I illustrate as an example the use of the removable rod D⁴ normally seated in the slots D⁵, by which it may be lifted from said slots when the hooks D⁶ are raised. In order to support the curtain laterally spaced away 60 from the window I provide as a convenient supporting means a rod or rods X which may be formed with notches X¹ at one end, to engage and support the rods D⁴, and slots X² to engage the pins or bolts X³ shown in Figure 4. These supporting members may be carried by the window-washer making 65 his rounds.

It will be realized that whereas I have 70 shown a practical and operative device, that nevertheless many changes may be made in the size, shape, number and disposition of parts without departing from the spirit of my invention. I therefore wish my description and drawings to be taken as in a broad sense illustrative or diagrammatic rather than as limiting me to my specific showing.

The use and operation of my invention are 75 as follows:

A frequent cause of annoyance, with the use of long curtains comes from the fact that when the sash of the window is raised the curtain is likely to blow out through the window, or at least hangs down across the 80 open window where it may be rained upon or, in dry weather, becomes dusty and dirty from flying dust, grit and soot.

The present application, which is directed to an improvement upon the structure of 85 my co-pending application 85,585, filed on February 2, 1926, shows means for automatically lifting the lower part of the curtain with the sash and therefore for preventing the curtain from being blown out of the 90 window or from being rained upon through the window or even from being subjected to the inflowing air currents. In the preferred form of my device the result of the initial upward movement of the sash is a lifting 95 of the bottom of the curtain at a more rapid rate than the rate of movement of the sash. This has for purpose to lift the bottom of the curtain so high as to be above the sash bottom and therefore out of the line of the 100 105 110

inflowing air. When this initial lifting is completed the curtain may be lifted at the same rate of movement as the sash.

The present application shows a peculiarly simple and easily manufactured means for carrying out my purpose in which a minimum number of parts are used. In the device herein shown the curtain may be supported at its upper end in any satisfactory manner. The curtain lifting mechanism may be positioned at any point along the length of the curtain but it is herein illustratively shown as positioned adjacent the top of the lower sash. I illustrate a pair of levers D^1 pivoted upon opposite sides of the lower sash C^1 . E^1 are stops or cams secured to the window frame above the sash and preferably so formed and positioned as to engage the short arm D^3 of each lever D^1 . Each stop or cam E^1 is continued by a track E . When the sash is in the position shown in Figure 1 or 2, the long arm D^2 of each lever depends, as shown in full line in Figure 2, the downward rotation being shown as limited by the engagement of the member D^3 with the cam E^1 . Any lifting movement of the sash will cause the initial rotation of each lever into the position shown in dotted line in Figure 2. This rotation folds up the curtain, as shown in Figure 2. Preferably the rod D^4 is threaded through the curtain or is secured to it in such a fashion that the curtain cannot slide in relation to the rod but is positively lifted when the rod itself is lifted by the rotation of the levers. When the levers have been lifted to the position shown in dotted line in Figure 2 the member D^3 slides along the track E . Thus after the initial rotation of the levers, which lifts the lower edge of the curtain more rapidly than the rise of the sash, further movement of the curtain will be at the same rate of movement as that of the sash.

In order to permit cleaning of the window I provide removable securing means for example the hooks D^6 , which permit the rod D^4 to be removed from the holding notches D^5 in the ends of the levers D^1 . Obviously I do not wish to be limited to the removal of the rod with the curtain, but I illustrate it as the preferred form of my device.

I claim:

1. In combination with a window having a vertically movable sash and a curtain, a curtain raising element including a portion normally in engagement with said curtain, and means for raising and lowering said curtain raising element in response to the raising and lowering of said sash, said curtain raising element including a transverse bar normally held against movement in relation to said curtain.

2. In combination with a window having a vertically movable sash and a curtain, a

curtain raising element including a portion normally in engagement with said curtain, and means for raising and lowering said curtain raising element in response to the raising and lowering of said sash, said curtain raising element including a transverse bar threaded through said curtain.

3. In combination with a window having a vertically movable sash and a curtain, a curtain raising member in engagement with the curtain intermediate top and bottom of the curtain, said member including a transverse rod, pivoted supporting levers at the ends thereof, and means for actuating said supporting levers in response to the upward movement of the sash, said rod being removably supported upon said levers.

4. In combination with a window having a vertically movable sash and a curtain, a curtain raising member in engagement with the curtain intermediate top and bottom of the curtain, said member including a transverse rod, pivoted supporting levers at the ends thereof, and means for actuating said supporting levers in response to the upward movement of the sash, said rod being removably supported upon said levers, the rod being adapted to receive and be supported by supplemental spacing members when the rod is removed from the levers.

5. In combination with a window having a vertically movable sash and a curtain, a curtain raising member in engagement with the curtain intermediate top and bottom of the curtain, said member including a transverse rod, pivoted supporting levers at the ends thereof and means for actuating said supporting levers in response to the upward movement of the sash, the rod being removably supported upon said levers, and supplemental spacing members adapted to be inserted between the rod and its normal supporting means.

6. In combination with a window having a vertically movable sash and a curtain, a curtain raising element in engagement with said curtain and means for raising and lowering said curtain raising element in response to the raising and lowering of said sash, said curtain raising element including arms projecting inwardly from the sash, and a transverse curtain engaging member removably supported on said arms.

7. In combination with a window having a vertically movable sash and a curtain, a curtain raising member in engagement with the curtain intermediate top and bottom of the curtain, said member including a supporting lever pivoted on the sash, and means for rotating said supporting lever in response to the initial upward movement of the sash, including a stop member mounted on the window frame and adapted to engage said lever when the sash is raised.

8. In combination with a window having

- a vertically movable sash and a curtain, a curtain raising member in engagement with the curtain intermediate top and bottom of the curtain, said member including a pivoted 5 supporting lever and means for rotating said supporting lever in response to the initial upward movement of the sash, through a predetermined arc and for thereafter constraining the curtain raising member to upward 10 movement in response to the continued upward movement of the sash, including a stop member, mounted on the window frame and adapted to engage the lever when the sash is lifted, and a guide member upon the window 15 frame, lying generally parallel with the axis of movement of the sash, and adapted to prevent retrograde rotation of the lever.
9. In combination with a window having a vertically movable sash and a curtain, a 20 curtain raising member in engagement with the curtain intermediate top and bottom of the curtain, said member including a supporting lever pivoted upon the sash, and means for rotating said supporting lever in 25 response to movement of the sash.
10. In combination with a window having a vertically movable sash and a curtain, a curtain raising member in engagement with the curtain intermediate top and bottom of the curtain, said member including a supporting lever pivoted upon the sash, and means for rotating said supporting lever in 30 response to movement of the sash, including 35 a stop mounted adjacent said sash and adapted to engage said lever when said sash is lifted.
11. In combination with a window having a vertically movable sash and a curtain, a curtain raising member in engagement with the curtain intermediate top and bottom of the curtain, said member including a supporting lever pivoted upon the sash, and means for rotating said supporting lever in 40 response to movement of the sash, through a predetermined arc, and for thereafter constraining said lever to non-rotary upward 45 movement with the sash.
12. In combination with a window having a vertically movable sash and a curtain, a curtain raising member in engagement with the curtain intermediate top and bottom of the curtain, said member including a supporting lever pivoted upon the sash, and means for rotating said supporting lever in 50 response to movement of the sash, through a predetermined arc, and for thereafter constraining said lever to non-rotary upward 55 movement with the sash, including an inclined stop mounted adjacent said sash and a generally vertical guide member extending 60 upwardly therefrom.

Signed at Chicago county of Cook and State of Illinois, this 20th day of November, 1926.

CHARLES M. HEUBLEIN.
